UNITED STATES PATENT OFFICE.

MATHIAS KLEINBAUER, OF CHICAGO, ILLINOIS.

SPIRIT-LEVEL.

No. 885,762.

Specification of Letters Patent. Patented April 28, 1908.

Application filed September 12, 1907. Serial No. 392,506.

To all whom it may concern:

Be it known that I, MATHIAS KLEINBAUER, citizen of the United States, residing at Chicago, in the county of Cook and State of Illinois, have invented certain new and useful Improvements in Spirit-Levels, of which the following is a specification.

This invention relates to spirit levels and has for its object to provide improved means for supporting the glasses and for adjusting the same, as hereinafter more fully explained.

The invention is illustrated in the accompanying drawing, in which,

Figure 1 is a plan view thereof. Fig. 2 is an edge view of the plates, which hold the glasses in place. Fig. 3 is a section on the line 3—3 of Fig. 1.

The straight edge bar or beam of the spirit level is indicated at 1, and a metal frame 20 which holds four spirit glasses 3 is composed of opposite plates 5 and 6. These are preferably square in form and have a circular opening at the center around which is an inwardly projecting annular flange or shoulder 25 7. These plates fit in suitable rabbets formed on opposite sides of the bar 1 and they are fastened together by means of screws 11 which extend through holes in the corners of the plate 6 and into taps in the ends of posts 30 9 projecting across from the inner side of the plate 5. These posts serve to space the plates apart, and also receive the screws as stated. The four glasses 3 are arranged to form a square and are held within a circular casting 13 which fits between the shoulders 7 on the face plates. This casting is circular 35 at its outer edge, but it has a central opening which is squared and which is cut away on each side to exhibit the bubble of the spirit 40 levels. The annular casting 13 is provided on each side with opposite segmental lugs or projections 14 which fit within the circular openings in the face plates. The short segments 14 are advantageous as compared with 45 a full ring, since a full ring would not fit as accurately to the circular holes in the plates 5 and 6 as the segments or lugs as shown, and the adjustment would be more difficult. Diagonal cross bars 17 extend between the cor-

ners of the square formed in the casting 13 50 and at the center support a socket 15 which is adapted to receive a key whereby the casting may be turned to adjustment.

The manner of adjustment is as follows:— By loosening the screws 11 the plates 5 and 55 6 will be loosened and the central casting 13 which holds the glasses, can be turned freely between the shoulders 7, and when properly set or adjusted the screws will be tightened, and the shoulders 7 will press against the 60 ring 13 and so hold the same in place. By placing a key in the socket 15 a very fine adjustment can be obtained, particularly if the screws 11 are loosened only slightly, so that considerable friction will exist, which 65 will prevent any slip incident to looseness after the glasses are once set.

I claim:

1. In a spirit level, the combination of opposite face plates having circular openings 70 therein, means connected to the respective plates to draw the same together as a clamp, a ring clamped between the plates and capable of being turned to adjustment, and having lateral projections fitting within and 75 against the edges of said openings, and a level glass carried by said ring.

2. In a spirit level, the combination of opposite face plates having circular openings 80 therein, screws connecting the plates to draw the same toward each other, a rotatable ring clamped between the plates and having segmental projections fitting within said openings, to center the ring, and a level glass carried by said ring. 85

3. In a spirit level, the combination of opposite face plates, an annular holder clamped between said plates and having a socket supported at the center and adapted to receive a key to turn said holder, and a 90 level glass carried by said holder.

In testimony whereof I affix my signature, in presence of two witnesses.

MATHIAS KLEINBAUER.
